UNITED STATES PATENT OFFICE.

OTIS A. MYGATT, OF NEW YORK, N. Y.

GLASSWARE.

1,093,719.

Specification of Letters Patent. Patented Apr. 21, 1914.

Application filed June 25, 1907. Serial No. 380,763.

To all whom it may concern:

Be it known that I, OTIS A. MYGATT, a citizen of the United States, residing in New York city, in the county of New York and State of New York, have invented certain new and useful Improvements in Glassware, of which the following is a specification.

The object of my invention is to produce 10 a rich iridescent coloring in glassware.

The invention consists in the arrangement and disposition of the prisms upon the opposite sides of the walls of the glassware whereby iridescent or spectrum-forming 15 iridescent effects are produced, the details of which will first be fully described and the patentable features therein set forth in the claims.

In the drawings: Figure 1 represents a 20 side elevation of a tumbler to which I have applied my improvements. Fig. 2 is a top view. Fig. 3 is a similar top view of the modified form. Fig. 4 is a plan view of a plaque, plate or reflector embodying a further modification of my invention.

In Fig. 1 is shown a tumbler, for example, having a series of 140° prisms running longitudinally upon its outer side, and upon its inner side opposite thereto a similarly 30 disposed series of prisms of 90° . The angle through the body or wall of the glass between the 140° prism on one side and the 90° prism upon the other being 65° .

In Fig. 3, the outer prisms are 120° and the 35 inner prisms are the same. The angle between the outer and inner prisms, which are opposite each other, is 60° across the body or wall of the glass.

In Fig. 4 the series of outer radial prisms 40 are 90° and the series of inner radial prisms are 140° , making an angle between the inner and outer prisms of 65° .

I have found that where prisms are used upon the wall or body of a glass opposite

each other so as to present across the body 45 of the glass an angle of 60 or 65 degrees, that the white rays of light are broken up into colors of the spectrum and rich iridescent effects are produced. This critical angle varies around 60° or 65° , depending 50 upon the refractive quality of the glass batch employed in forming the glassware. The higher the refracting power of the glass batch used, the smaller the angle necessary to break up the white light in the colors of 55 the spectrum is required.

I claim:

1. Glassware having prismatic surfaces upon both sides of the glass body, the angle of the sides of those surfaces opposite each 60 other constituting spectrum forming angles.

2. Glassware having prismatic surfaces upon both sides, the angle of the sides of those surfaces opposite each other forming angles of about 60° . 65

3. A transparent glass inclosure having prismatic surfaces upon both sides, the angle of the sides of those surfaces opposite each other constituting spectrum-forming angles.

4. Inclosures having prismatic surfaces 70 upon both sides of the glass body, the angle of the sides of those surfaces opposite each other constituting spectrum forming angles.

5. An inclosure having prismatic surfaces upon both sides, the angle of the sides of 75 those surfaces opposite each other forming angles of about 60° .

6. An inclosure for artificial lights having prisms upon both surfaces lying in planes passing through the inclosure axis, 80 the sides of the prisms on the outer surface forming angles of about 60 degrees with the sides of the prisms on the inner surface.

OTIS A. MYGATT.
